[57] CLAIM

An ornamental design for a wood splitter, substantially as shown and described.

DESCRIPTION

FIG. 1 is a perspective view of the wood splitter embodying our new design.

FIG. 2 is a side elevation view thereof.

FIG. 3 is an end elevation view of the right end of the wood splitter shown in FIG. 2.

FIG. 4 is an end elevation view of the left end of the wood splitter shown in FIG. 2.

FIG. 5 is a plan view thereof.
